UNITED STATES PATENT OFFICE.

STEPHEN H. FARNHAM AND ARTHUR W. SMITH, OF NEW YORK, N. Y., AND JOSEPH PHELPS, OF BELLEVILLE, NEW JERSEY, ASSIGNEES TO REMINGTON TYPEWRITER COMPANY, OF ILION, NEW YORK, A CORPORATION OF NEW YORK.

TYPE-WRITING MACHINE.

1,096,027.

Specification of Letters Patent.

Patented May 12, 1914.

Original application filed January 18, 1913, Serial No. 742,786. Divided and this application filed May 12, 1913. Serial No. 767,204.

To all whom it may concern:

Be it known that we, STEPHEN H. FARNHAM, ARTHUR W. SMITH, and JOSEPH PHELPS, citizens of the United States, and 5 residents, respectively, of the borough of Brooklyn, county of Kings, city and State of New York; borough of Manhattan, city, county, and State of New York, and Belleville, county of Essex, and State of New Jersey, have invented certain new and useful Improvements in Type-Writing Machines, of which the following is a specification.

Our present invention relates to paper 15 gage or paper stop devices for typewriting machines and its general object is to provide new and improved devices of the character specified.

To the above and other ends our invention 20 consists in the features of construction, combinations of devices and arrangements of parts hereinafter described and particularly pointed out in the claims.

The present application is a division of 25 our prior application, Serial No. 742,786, filed January 18, 1913, and which has eventuated in Patent No. 1,071,612, granted August 26, 1913, and while the principles of our present invention are applicable to typewriting machines generally, the preferred embodiment of said invention as herein illustrated is especially adapted to the typewriting machine disclosed in said prior application.

35 In the accompanying drawings illustrating our invention, Figure 1 is a fragmentary end view partly in section of the upper part of a typewriting machine embodying our invention. Fig. 2 is a face view of our novel side gage and its mounting. Fig. 3 is a transverse sectional view taken on a plane indicated by the dotted line *t-t* in Fig. 2 and looking in the direction of the arrow at said line. Fig. 4 is a sectional view taken on a plane indicated by the dotted line *s-s* in Fig. 3 and looking in the direction of the arrows at said line. Fig. 5 is a fragmentary face view partly in section of our novel end gage and its mounting. Fig. 6 is a detached view of one of the elements of said end gage.

As shown in Fig. 1 a carriage comprising end bars 26 and 27 and cross bars 29 and 30 is adapted to coöperate with fixed grooved

guide rails on the main frame of the machine. One of said guide rails 33 is shown 55 fixed above the rear part 11 of the top plate of the machine, said guide rail being grooved to coöperate with the grooved carriage bar 29 through anti-friction rollers 31. Said carriage supports a rotary platen 36 60 provided with paper guiding devices comprising a deflector 106 which curves around the under side of said platen and a paper table 114 arranged at the rear side of the platen and suitably mounted on said carriage, the lower edge of said paper table being contiguous to the upper edge of the deflector 106. The details of the carriage construction are fully disclosed in said prior application.

A side gage or guide of novel construction is provided for the sheet or sheets that are fed over the paper table 114 and around the platen 36. Said side gage as shown in Figs. 1 to 4 is mounted on a grooved track-way 124 suitably secured to the left-hand side of the paper table 114 near its lower edge. Said track-way extends horizontally along the paper table and receives a slide 125 to which is suitably secured as by rivets 80 125^a a spring plate 126, the upper and lower end portions whereof respectively coöperate frictionally with the paper table 114 and deflector 106 so as to maintain the slide in adjusted positions along the track-way 124. 85 Suitably secured to the slide 125 as by being screwed at 125^b to an ear 125^c on said slide is an upstanding side gage or guide proper or abutment 127. A lateral pin 128 on this abutment or gage plate 127 is adapted to co- 90 operate with a feed roll release lever 104 or other suitable relatively stationary part to prevent the slide from being detached at the left from its guide way 124. The friction plate or device 126 is of very thin flexible sheet metal and while it overlies or covers the guide way 124 and the slide 125, its upper and lower portions incline down toward the paper table and paper deflector and closely hug these parts so that when 100 paper, and particularly that sort provided with key hole slots or punches at its margin, is introduced downward into the main carriage over the paper table 114, its edges will not be obstructed by the projecting upper edge or face of the part 124 but will be

guided over the same by the inclined upper portion of the friction plate. Thus the friction plate not only serves to hold the side gage 127 securely in adjusted positions along the guide way but also serves in itself as a paper guide to facilitate the handling of the paper or work sheets.

Mounted for endwise movement on the main carriage comprising the end bars 26 and 27 is a sub-carriage comprising a base plate 183 provided with upturned end plates 183^a (Fig. 1). Said sub-carriage is hung or supported from the cross bar 30 of the main carriage which is provided with a groove 184 with which coöperate rollers 185 mounted on the base plate 183. Said sub-carriage supports paper guiding and controlling devices comprising, as appears in Fig. 1, a guide plate 224 slotted for the accommodation of a feed roller 233 which is pivotally supported on the sub-carriage and coöperates with a feed roller 238 to feed paper over the guide plate 224 and across the printing face of the platen 36, said paper, indicated at 477, being superposed on the paper fed over the main platen. The sub-carriage paper 477 is contained or housed in a basket or receptacle 208 mounted on the sub-carriage and arranged below the same, its upper part being in line with the paper guide plate 224. A flexible finger 209 coöperates with said basket to direct the paper downward into the latter; said finger holding the paper lightly against the front face of said basket. The basket 208 is provided with a side paper gage 210 at its left-hand side and with an end stop device or gage which is adjustably mounted on the basket and extends from side to side thereof.

The end gage proper is shown in Figs. 1, 5 and 6 and comprises a squared rod or bar 215 which is arranged within the basket and transversely thereof, being movably mounted on a carrier or bail 216 of spring metal, the tendency of the bail being to bow upward as will be understood from Figs. 1 and 6. The bail is arranged outside the basket and its upturned ends or ears 216^a are formed with holes which receive screw pintles 217 projecting from the ends of the bar 215. Arranged within the basket forward of the bar is a roller 218 provided with a rubber sheath 219, the ends of the roller being reduced as indicated at 220 and bearing in openings in the ears 216^a. Outside the left ear the reduced end has secured to it a knurled finger button 221. Just inside of each ear the ends 220 have secured to them small toothed wheels, gears or sprockets 222. These wheels are rotatably adjustable relatively to each other, and to this end one at least is set on the associate reduced end 220 by a set screw 220^a. The teeth of the sprockets 222 are

adapted to coöperate with rack devices or series of holes 223. There are two sets or series of holes 223, one for each sprocket, said holes being punched or otherwise formed in the basket 208 near its edges. By turning the finger button 221 the sprockets are turned together and will coöperate with the holes 223 to effect a positive feed or advance of the carrier or bail 216 and the end stop 215, the construction providing a positively operating rack and gear connection between the end stop device and its support at each end of the end stop device. The feed of each end of the stop device will therefore be equal and skewing of the stop bar 215 is prevented. The stop device will be held in adjusted positions chiefly by the friction between the body of the bail 216 and the face of the basket. The rubber roller 218, 219 facilitates ease, smoothness and silence in the adjusting operation. The paper, it will be understood, is introduced into the basket and between it and the spring finger 209 and is adjusted against the side gage 210, being pressed downward into the basket until arrested by the stop bar 215 which will not only give the proper initial location endwise but will also square or true the sheet, coöperating with the same along its entire end or edge portion to effect this result.

Our present invention provides new and improved gage devices which are capable of varying use in writing machines, and it will be understood that certain of said devices may be used without other devices and also that various changes may be made without departing from the scope of our invention.

The claims in the present case relate to gage or stop devices, other features herein disclosed being claimed in the prior parent application aforesaid or in other divisional applications based on said parent application.

What we claim as new and desire to secure by Letters Patent, is:—

1. In a typewriting machine, the combination of a platen carrier, a platen thereon, a guide way movable with said carrier, a paper side guide slidable on said guide-way, and a friction plate secured to said side guide and overlapping said guide-way, the paper passing over said friction plate in contact therewith and being supported thereby.

2. In a typewriting machine, the combination of a platen carrier, a platen, a paper table or guide plate, a guide-way on said table and extending along said table, a slide on said guide-way, a paper gage on said slide, and a friction plate secured to said slide and coöoperative with said paper table, said friction plate extending transversely of and overlying said guide-way, the paper passing over said friction plate in contact therewith and being supported thereby.

3. In a typewriting machine, the combination of a platen carrier, a platen, paper deflecting and supporting means, a grooved guide way mounted on said means and projecting above the surface thereof, a slide in said guide-way, a paper gage on said slide, and a flexible friction plate secured to said slide and overlying said guide-way, the end portions of said friction plate inclining to ward and coöperating with said means, the paper passing over said friction plate in contact therewith and being supported thereby.

4. In a typewriting machine, the combination of a platen, a paper end gage, a support therefor, and sets of rack and gear connections between said support and said gage, one set near each end of the latter, said connections being hand controlled and operative to vary the position of said gage on its support.

5. In a typewriting machine, the combination of a platen, a paper end gage, a support therefor, independent sets of positive connections between said support and said gage, one set near each end of the latter, and means for affording variation in the relationship of one of said sets of connections with the other set.

6. In a typewriting machine, the combination of a platen, a paper end gage, a support therefor, rack and gear connections between said support and said gage near each end of the latter, and a carrier for said gage having a frictional connection with said support.

7. In a typewriting machine, the combination of a platen, an end gage for the paper, supporting means for said gage, two sets of devices for positively connecting said gage adjustably with its support, and means for

affording variation in the relationship of one set with the other.

8. In a typewriting machine, the combination of a platen, an end gage for the paper, supporting means for said gage, two sets of devices for positively connecting said gage adjustably with its support, each set comprising a gear wheel, and means for affording variation in the relationship of said gear wheels.

9. In a typewriting machine, the combination of a platen, an end gage bar for the paper, a supporting plate for said bar, and a bail supporting said bar and coöperating frictionally with said plate.

10. In a typewriting machine, the combination of a platen, an end gage bar for the paper, a guide plate, a bail supporting said bar and coöperating frictionally with said plate, gears mounted on said bail at its ends, and coöperating rack devices on said plate.

11. In a typewriting machine, the combination of a platen, an end gage bar for the paper, a supporting plate for said bar, a bail supporting said bar and coöperating frictionally with said plate, a roller on said bail and coöperating with said plate at the face opposite said bail, gears at the ends of said roller, a finger piece for rotating said roller and said gears, and rack devices on said plate coöperative with said gears.
